UNITED STATES PATENT OFFICE.

FRIEDRICH SIEMENS, OF BERLIN, GERMANY.

FURNACE.

1,098,985.

Specification of Letters Patent. Patented June 2, 1914.

Application filed June 13, 1912. Serial No. 703,554.

To all whom it may concern:

Be it known that I, FRIEDRICH SIEMENS, a citizen of the German Empire, residing at Berlin, in the Kingdom of Prussia, Germany, have invented certain new and useful Improvements in Furnaces; and I do hereby declare the following to be a full, clear, and exact description of the invention, such as will enable others skilled in the art to which 10 it appertains to make and use the same.

My invention relates to improvements in open hearth furnaces of the regenerative or recuperative type, and more particularly in open hearth furnaces of that class, in which 15 the hearth consists of two sections adapted to be heated to different temperatures, and in which a part of the flame heating the section of higher temperature is directed through the section of lower temperature, 20 while the remaining part of the said flame is used for heating the regenerator or recuperator. A furnace of this class has been described in my Austrian Patent No. 51,838 dated March 10, 1910. As explained in the 25 specification of the said patent, the flame which passes exclusively through the chamber of the furnace of higher temperature has a form which is similar to a horse shoe located in a horizontal plane.

One of the objects of the improvements is to provide a furnace of this class in which the flame is not necessarily formed in a 30 horizontal plane, but can assume any desired position relatively to the hearth or furnace. Thereby my improved system can be put to use under various conditions under 35 which it can not be used when the flame is formed in a horizontal plane.

When heating in the furnace materials 40 which give off much dust, the flame which is taken from the chamber of higher temperature and directed through the regenerators carries along much dust whereby the regenerators are rapidly choked. To avoid 45 this I prefer to provide a subsidiary chamber in front of the discharge ends of the burners and intermediate the latter and the heating chamber of the furnace, and to directly connect the said subsidiary chamber 50 with the regenerators, so that the regenerators are heated by gases which have not been in contact with the material to be heated, and which are therefore free of dust. 55 The gases are conducted in such a way, that they are divided within the chamber which is provided between the discharge of the

burners and the hearth and does not receive the material to be heated, one part of the gases passing directly through the regenerator and another one through the whole 60 furnace.

In order that my invention may be more clearly understood several examples embodying the same have been shown in the accompanying drawings, in which the same 65 letters of reference have been used in all the views to indicate corresponding parts.

In said drawings Figure 1, is a vertical cross-section of a furnace in which the flues for admitting and withdrawing the heating 70 gas are disposed vertically and laterally and on opposite sides of the section of the hearth of high temperature, so that the horse shoe shaped flame is formed in a vertical plane perpendicular to the longitudinal axis of the hearth, Fig. 2, is a horizontal section of the furnace shown in Fig. 1, Fig. 3, is a longitudinal section of a furnace in which the inlet and outlet flues are disposed at the rear 75 and on opposite sides of a subsidiary chamber located at the rear of the hearth, and in which the upper wall of the said chamber is inclined forward and upward, so that the flame is formed in an inclined plane, Fig. 4, is a horizontal section of Fig. 3, Fig. 5, is a 80 longitudinal section of a furnace in which the inlet and outlet flues are disposed at the rear of the hearth and above each other, so that the flame is formed in a vertical plane located in the direction of the longitudinal 85 axis of the furnace, Fig. 6, is a horizontal section of Fig. 5, Fig. 7, is a longitudinal section of the rear part of a furnace in which the inlet and outlet flues are disposed at the rear of the hearth and above each other and 90 in which a plurality of pairs of flues are disposed in such a way, that the flame forms a double horse shoe, Fig. 8, is a horizontal section of Fig. 7, Fig. 9, is a longitudinal section of a furnace provided at the rear of 95 the hearth with a subsidiary chamber and having a pair of flues disposed at the rear of and on opposite sides of the subsidiary chamber, and Fig. 10, is a horizontal section of Fig. 9.

Referring to the example illustrated in Figs. 1 and 2, the hearth of the furnace consists of a section *m* of higher temperature and a section *n* of lower temperature. The material is gradually advanced through the section *n* to the section *m* while being heated 100 to the desired temperature. The heating 105

gas and air are supplied to and withdrawn from the section *m* alternately through flues or passages *a* and *b* disposed at opposite sides of the said section. As shown the flues are disposed vertically so that the flame passes through the section *m* in a direction substantially perpendicular to the direction of the movement of the material, and in the form of a flat bow disposed in a vertical plane, as is indicated by the arrows shown in Fig. 1. A part of the flame is directed through the section *n* of lower temperature, as is indicated in Fig. 2.

In the modification shown in Figs. 3 and 4 the flues *a'* and *b'* are disposed at the rear end of the section *c'* of higher temperature and the part of the top wall of the section *c'* adjacent to the flues is inclined upward and forward, so that the flame can follow its natural tendency to move upward. Therefore the horse shoe flame is formed in an inclined plane, and the chord of the arc formed by the flame is perpendicular to the longitudinal axis of the furnace. As shown the horse shoe shaped flame is formed within a subsidiary chamber *o* located at the rear of the hearth *c'*, and a part of the flame is withdrawn from the chamber without coming in contact with the material to be heated, while the remaining part passes over the hearth *c'*.

In the example shown in Figs. 5 and 6 the flues *a²* and *b²* for the gases of combustion are disposed at the rear of the hearth and vertically above each other. Thereby the flame is formed in a vertical plane and its incoming and return branches are parallel to the longitudinal axis of the furnace. The incoming branch of the flame falls on the material from above, whereby in case of an oxidizing flame oxidation of the material is assisted.

Figs. 7 and 8 show an example in which the flame is formed in a similar way as in Figs. 5 and 6. But instead of being provided with a single pair of burners, as in the example shown in Figs. 5 and 6, the furnace is provided with a plurality of pairs of burners. As shown three burners are provided, and the gas enters the furnace from a chamber *d* and is mixed with the combustion air which is admitted through a passage *e* disposed above the chamber *d*. Thereby a flame is formed which is divided into two branches flowing to opposite sides of the furnace. The flame has the form of a double horse shoe. From the incoming branch of the flame a part is directed through the hearth section of lower temperature, and two returning branches are withdrawn through the flues *b⁸* and *f*. Figs. 7 and 8 also show, that my improved system may also be used in a furnace provided with recuperators. In this case the admission of the combustible gases can not be reversed,

but always takes place through the same burners.

In the furnace shown in Figs. 9 and 10 the subsidiary chamber *g* is constructed in a more distinct manner, than in the example shown in Figs. 3 and 4. The flues *a⁴* and *b⁴* are disposed at the rear of and at opposite sides of the subsidiary chamber. Within the chamber *g* the flame is divided in a manner similar to the example shown in Figs. 5 and 6. A small part of the flame has the form of a horse shoe and is directed through the outlet flues *h*, while the major part passes over the hearth. The subsidiary chamber *g* is preferably provided in furnaces for roasting iron or zinc ores, for burning cement, for fritting ores and powder of slag. Any suitable means may be provided for feeding the material toward the flame.

The subsidiary chamber may be used in any of the furnaces described above and also in a furnace in which the flame is formed in a horizontal plane.

From the description it will be understood, that my improved system may be used under various conditions. The construction of the furnace does not depend upon a determined plan, and it adapts itself to various local conditions and to the space which is at disposal for the construction of the furnace. For example a welding furnace may be connected with a plurality of chambers of lower temperature, within which articles of small size may be heated. In a furnace of the construction described in my Austrian patent only one of the heating chambers would receive the whole flame, viz. the chamber located at the side of the discharge of the flame. Also in other cases it is necessary to symmetrically distribute the flame, which is possible only where the furnace is constructed according to my improved system. In some cases it is necessary to subject the material to be heated to a heavy oxidation. In such cases the horse shoe flame is formed in a vertical plane so that it is always directed against the material located within the welding furnace. Other uses of my improved furnace will readily suggest themselves to those skilled in the art.

By providing a subsidiary chamber I am able to supply the regenerators with gases which are free of dust. Apart from this an important advantage is obtained where materials are to be treated which do not give off any dust. For example, in a furnace of the construction so far described in which no subsidiary chamber is provided, it is impossible to work under pressure. However, in a welding furnace it is very desirable, if not absolutely necessary, to work under pressure. Obviously at the part of the furnace where the flame is being divided a

vacuum must be produced. When withdrawing the heated material from the furnace cold air is drawn in through the doors or other openings of the furnace which must necessarily be provided at the said part of the furnace. However the admission of cold air is very objectionable. By separating the flame within the subsidiary chamber the furnace itself can be held under pressure. The said subsidiary chamber should not have any connection with the atmosphere. It will therefore be understood, that by providing my improved furnace with a subsidiary chamber it may be worked under pressure.

In all of the figures of drawing the walls of the furnaces illustrated confine the gases in the furnace and afford means adjacent the air and gas ports that coöperate therewith, or assist in directing the gases from one port or set of ports to the other port or set of ports.

I claim herein as my invention:

1. The combination in an open hearth furnace, of air and gas ports arranged to coöperate with the furnace structure to direct a reversing flame over a portion of the hearth out of its normal horizontal plane.

2. The combination in an open hearth furnace, of air and gas ports arranged to coöperate with the furnace structure to direct a reversing flame over a portion of the hearth out of its normal horizontal plane, and means to cause a portion of said flame to extend longitudinally over the hearth.

3. The combination in an open hearth furnace, with a continuous hearth and regenerators; of air and gas ports coöoperating with the furnace structure and arranged to direct a reversing flame across a portion of the hearth out of its normal horizontal plane and normal direction between the regenerators.

4. In an open hearth furnace, the combination with a continuous hearth and regenerators, of air and gas ports arranged to coöperate with the furnace structure to direct

a reversing flame across a portion of the hearth out of its normal horizontal plane and normal direction between the regenerators, and another portion of said flame longitudinally over the remaining portion of the hearth.

5. In an open hearth furnace in combination; a hearth, air and gas ports, and means coöoperating therewith to direct the flame over a portion of the hearth into a plurality of reversed portions.

6. In an open hearth furnace in combination; a hearth, air and gas ports, and means coöoperating therewith to divide the flame over a portion of the hearth into a plurality of reversed portions directed out of their normal path in planes at an angle to the horizontal.

7. In an open hearth furnace, the combination with the hearth and air and gas ports; of means coöoperating with said ports to divide the flame into a plurality of reversed portions directed transversely of the hearth in planes at an angle to the horizontal.

8. In an open hearth furnace, the combination with the hearth and air and gas ports; of means coöoperating with said ports to divide the flame into a plurality of reversed portions directed transversely of the hearth in planes at an angle to the horizontal, and means to direct a portion of the flame longitudinally of the hearth.

9. In an open hearth furnace in combination; the hearth, the air and gas ports thereof, and means coöoperating with said ports to direct all of the flame over the initial portion of the hearth, a portion of said flame being reversed and deflected from its normal path and means to cause another portion to extend over the entire hearth.

In testimony whereof I hereunto affix my signature in the presence of two witnesses.

FRIEDRICH SIEMENS.
